(57) **CLAIM**

The ornamental design for point of sale terminal, as shown and described.

DESCRIPTION

Point of sale terminal

1 : Perspective
 2 : Front
 3 : Back
 4 : Left
 5 : Right
 6 : Top
 7 : Bottom

The broken lines in the drawings illustrate portions of the point of sale terminal which forms no part of the claimed design.

The designs are used in the fields of finance, e-commerce, cashier and so on; the products have the function of electronic payment/barcode scanning/printing bills by reading IC card/magnetic stripe card/non-access card, etc.

1 Claim, 7 Drawing Sheets
